TABLE ACCORDION

Mario Pancotti, Scarsdale, N.Y.

Application October 21, 1958, Serial No. 53,058

Term of patent 14 years

(Cl. D56—1)

Fig. 1 is a front elevational view of a table accordion, showing my new design;

Fig. 2 is a top plan view thereof;

Fig. 3 is a right end view thereof; and

Fig. 4 is a sectional view taken on line 4-4 of Fig. 2. The rear of the device is substantially plain.

I claim:

The ornamental design for a table accordion, substantially as shown and described.
